UNITED STATES PATENT OFFICE.

CLINTON H. MALTBY, OF DAYTON, OHIO, ASSIGNOR TO THE NATIONAL MANUFACTURING COMPANY, OF SAME PLACE.

FARE-BOX, INDICATOR, AND RECORDER.

SPECIFICATION forming part of Letters Patent No. 311,019, dated January 20, 1885.

Application filed May 5, 1884. (No model.)

To all whom it may concern:

Be it known that I, CLINTON H. MALTBY, a citizen of the United States, residing at Dayton, in the county of Montgomery and State 5 of Ohio, have invented certain new and useful Improvements in Fare Boxes and Registers, of which the following is a full, clear, and exact description, reference being had to the accompanying drawings, forming a part 10 of this specification.

My invention relates to that class of fare-boxes which are designed more particularly for use on street-cars, omnibuses, and like public vehicles, but also capable of use in 15 other places where it is desired to deposit fares, and has for its object, primarily, the combination, with the locked permanent receptacle and the temporary retaining and inspecting receptacle, of indicating and recording mechanism operated by a series of keys or levers under control of the driver or person in charge, whereby the deposited fares and tickets temporarily arrested in the inspection-chamber by the successive operation of the 20 keys and levers have their respective values indicated successively by means of projected and disclosed tablets, which values, by the same operation that discloses them, are permanently recorded, which indicating and recording take place while the fares remain in 25 the inspection-chamber, so that the occupants of the car or the persons paying can see that all are properly indicated and recorded, after which, by the operation of another and independent lever, the fares and tickets are 30 released and fall into the permanent locked receptacle.

The novelty of my invention consists in a fare-box having in combination the permanent locked receptacle, a temporary arresting inspection-chamber, and indicating and recording mechanism operated by a series of levers or keys of fixed values, whereby any number of deposited fares arrested in the 35 inspection-chamber must have their values indicated to the persons paying and be permanently recorded before they are deposited in the closed locked receptacle; also, in the con-

struction and combinations of the parts, all as will be herewith set forth and specifically 50 claimed.

In the accompanying drawings, Figure 1 is a perspective view of my improved fare box and register. Fig. 2 is a central vertical sectional view in side elevation of the same. 55

The same letters of reference are used to indicate identical parts in both figures.

I preferably construct the box of the shape shown, though this may be varied without affecting my invention, and would describe it 60 as having, essentially, first, a lower receptacle, containing, preferably, a locked drawer, A, and with a hinged door, B, adapted to close the receptacle and be locked by a padlock or other suitable lock, C, and having also 65 an opening, a, in its upper wall, to admit the tickets and fares into the drawer A or the lower locked receptacle; second, an inspection-chamber over the locked receptacle, having its front and rear walls composed of transparent glass or other transparent media, b and c, a deposit slit or opening, D, at its upper end, a fixed incline slide, E, located as shown, having its lower edge serrated or sharpened, a substantially-horizontal tilting platform, F, 70 and a second inclined glass or other transparent apron, G, and a lower substantially-horizontal or slightly-inclined reflecting-surface or mirror, H; third, an upper chamber containing the recording and indicating mechanism and their connections, to be hereinafter described, having a locked door, I, upon opening or removing which the recording mechanism is disclosed, and having also an extreme upper compartment 75 with transparent glass windows d e, into which and between the glass windows the indicating-tablets are projected and exposed to view whenever the levers or keys for registering the fares are operated. This registering and 80 indicating mechanism may be that shown and described in Letters Patent No. 271,363, dated January 30, 1883, to Ritty and Birch, or that shown in the pending application of myself, filed September 21, 1883, though I have here 85 illustrated it as that shown in the pending ap-

lication of James Ritty, filed September 21, 1883, the essential features of all of which are a series of levers or keys of fixed values, a series of tablets of corresponding values mounted on rods operated by said keys, and registering mechanism, and a gong or bell, with connecting mechanism, the parts being so constructed and arranged that whenever a key is operated to its farthest limit, and only then, its corresponding tablet is exposed to view and remains so exposed, and the bell or gong is sounded, and, further, that no tablet can be exhibited without its value being recorded upon the recording mechanism, and whenever any tablet is disclosed it remains so until another key is operated to expose another tablet.

The only difference between my present recording and indicating mechanism and those before referred to is that the keys or levers *J*, instead of projecting at their forward ends, project at their rear ends nearest the tablet-rod *K* through vertical slots in the metal plate *L*, and are operated by being lifted instead of by being depressed, as in the former cases. The outer ends of these levers have jointed extensions *J'*, provided with buttons marked with the value of each key or lever, as seen in Fig. 1. These extensions hang down close to the box and out of the way, and their hinging is, as shown, so as to form a practical knuckle-joint when they are raised. Any other method of hinging to accomplish this result might be employed.

The tablets are represented by *M*, their supporting-wing by *N*, the gong by *O*, the frame vibrated by the levers by *P*, the frame-retracting spring by *R*, the recording paper rolls by *S*, and the puncturing-point on each lever by *T*. The exact construction and mode of operation of this mechanism will be found in the Ritty application before referred to. The platform *F* is centrally pivoted at *f* to the sides of the box, and in its normal or horizontal position fills the space between the glasses *b* and *c*, as shown. In a recess in the side of the box, which recess is covered by a segmentally-slotted plate, *u*, is an arm or link, *g*, Fig. 2, whose upper end is pivoted to one of the arms, *h*, of the vibrating frame *P*, and whose lower end is pivoted upon a pin or lug extending from the platform *F* through the segmental slot *i*. From this construction it results that when any one of the levers *J* is operated the vibration of the frame *P*, caused thereby to operate the indicating and recording mechanisms, tilts the platform *F* to the position shown by the dotted lines, as will be readily understood. The retraction of the frame *P* by the spring *R* returns the platform *F* to its normal or substantially horizontal position.

The inclined apron *G* is pivoted at *j* in the sides of the box, and is vibrated by a bell-crank, *k*, recessed in the side of the box, with a projecting operating-button, *l*, hung at *j*, and

having a stud or pin, *m*, from the apron working in a segmental slot, *n*, and secured to the lower end of the bell-crank, as shown. Any suitable spring, *p*, serves to hold the arm *k* up and keep the apron with its lower edge in close contact with the glass *c* or front wall of the box, as shown.

V is an opening in the side of the box, covered by a grating, through which light at night may be admitted from a lamp to the inspection-chamber. In the present instance there are four levers *J*, whose buttons are marked "3," "5," "Half T," and "Ticket," respectively, meaning three cents, or half-fare, five cents, or whole fare, half ticket, and whole ticket, respectively.

The tablets are correspondingly marked, as well as the paper on the rolls *S*, and the operation is as follows: We will suppose that a three-cent piece, a five-cent piece, and a half-ticket have been deposited by passengers of a street-car. They are arrested upon the platform *F* and are exposed to the view of both the driver and the passengers. The driver thereupon proceeds to indicate and record them by first raising the three-cent lever. As he does so the platform *F* is tilted and all are dropped upon the apron *G*, where they still remain exposed to view, as seen in Fig. 1. He next operates the five-cent lever, thereby throwing up the five-cent tablet and recording the amount on the paper, and he finally operates the half-ticket lever, bringing into view the half-ticket tablet and recording the amount. Having recorded all the fares so far deposited, while they remain in full view, he depresses the button *l*, which swings back the apron *G* and permits them to drop into the drawer *A*. He may do this at once or may wait until other fares have been deposited on the platform *F*, as seen in Fig. 1; but before again tilting the platform *F* he should operate the apron *G*, as above stated. By this means an absolutely accurate register of all the fares is made in the presence of the passengers, whose attention is called thereto by the sounding of the gong every time a lever is operated; and this record, being inclosed and locked up, cannot be altered or tampered with, and must in every case correspond with the contents of the drawer *A*.

By placing the drawer-receptacle key in the possession of one employé and the record and mechanism receptacle key in the possession of another employé, an absolute check against dishonesty or mistakes is provided.

Having thus fully described my invention, I claim—

1. A fare-box having in combination a permanent locked receptacle, an inspection-chamber, into which the fares are introduced and temporarily arrested, and a recording and indicating mechanism, a series of levers, whereby the fares are indicated and recorded while arrested in the inspection-chamber, and

whereby, after they are recorded, they are deposited into the permanent locked receptacle, substantially as described.

2. In a fare-box having an indicating and recording mechanism and an inspection-chamber with two or more tilting platforms and a permanent locked receptacle, the combination, with the recording-mechanism-operating levers, of the upper tilting platform with connecting mechanism, whereby when any one of the levers is operated said platform is tilted, substantially as described.

3. The combination and arrangement of the

platform F, segmentally-slotted plate U, recessed arm or link g, vibrating frame P, and 15 operating-levers J, substantially as described.

4. In a fare-box having the indicating and recording mechanism and inspection-chamber, as herein described, the tilting platform and the lever mechanism which operates said 20 platform and indicates and records the fares, in combination substantially as described.

CLINTON H. MALTBY.
